AUTOMATIC ELECTRIC WATER HEATER

Filed Sept. 14, 1927

UNITED STATES PATENT OFFICE

MANSFIELD C. CRAWLEY, OF GROTON, NEW YORK, ASSIGNOR TO CHARLES D. DAVIS, OF WASHINGTON, DISTRICT OF COLUMBIA, AND WILLIAM R. DAVIS, OF WESTFIELD, NEW JERSEY

AUTOMATIC ELECTRIC WATER HEATER

Application filed September 14, 1927. Serial No. 219,494.

This invention relates to that type of electric water heating apparatus designed to maintain a supply of water heated to a predetermined desired degree, the electric heating means being operative when the water is below the predetermined temperature and being inoperative when the water is heated above the predetermined temperature. Water heating apparatus of this type is adapted for many uses where a supply of hot water is desirable. The apparatus shown and described herein is especially designed for household use.

An object of the invention is to provide a water heating apparatus having improved means for automatically controlling the electric heating current.

Another object of the invention is to provide for the automatic control of the heating current by means operated by hydrostatic pressure in response to changes in the temperature of the water.

In the drawings:

Fig. 1 is a vertical sectional view of the heating apparatus with the current-controlling parts in the positions for heating the water;

Fig. 2 a fragmentary vertical section upon a larger scale showing the current-controlling parts moved to interrupt the current; and

Fig. 3 a horizontal section taken on the line 3—3 of Fig. 2.

Referring by numerals to the various parts of the apparatus, 1 designates an upright closed water tank of suitable capacity. A plate 2 forms the lower end wall of the tank and is removably secured to the body of the tank by screws or bolts 3. A water inlet pipe connection 4 is threaded through the center of the plate 2, and an outlet pipe connection 5 is threaded into the upper end of the tank. Centrally formed upon the upper face of the plate is a circular boss 6. This boss is formed with a circular channel 7 which is concentric with the water inlet. The side walls of the channel 7 are undercut as at 8 and its bottom is formed with two spaced, concentric grooves 9. Disposed at the bottom of the channel 7 are two rings 10 and 11 of suitable

insulating material, the undersides of the rings being formed to fit in the grooves 9 and position the rings in spaced concentric relation. Two flat rings 12 and 13 of suitable conducting material are supported by the insulation rings 10 and 11 and to each of the former is connected a conducting rod 14. At its under face the plate 2 is formed with two bosses 15, and the insulation rings 10 and 11 are formed with tubular extensions 16 which extend downward through openings in the bosses. The rods 14 project through the extensions 16 and have nuts threaded upon their lower ends for clamping the current-conducting wires 17 and 18 thereto. Cap nuts 19 are threaded upon the bosses 15 and enclose said rods and conducting wires at their points of attachment.

Supported upon the conducting ring 12 is a tubular, cylindrical terminal or electrode 20, and supported upon the ring 13 is a smaller tubular, cylindrical terminal or electrode 21. These two terminals are formed of carbon. They are of the same height and are supported in spaced relation. A suitable fusible insulating material 22 is poured into the channel 7 to fill the latter and surround the lower ends of the terminals and the rings supporting them. This material flows into the undercut portions of the channel and through transverse openings 23 in the terminals. When it hardens the terminals are held rigidly in place. The carbon terminals are preferably coated except on their opposed faces with a suitable water-proof insulating enamel 24. This insulating material may be applied to the carbon terminals in any suitable manner, by baking or otherwise.

An upright open-ended tubular member 25 is threaded at its lower end into the center of the boss 6 in direct vertical alinement and communication with the water inlet. This tubular member extends to a point above the upper ends of the terminals and supports a closed water chamber 26. The latter is formed by a cylindrical upright tubular body 27, a closure cap 28 threaded upon the upper end of the body, and a plug 29 threaded into the lower end of the body. The plug 29 is formed with a downwardly extending 100

stuffing box 30, and a plunger 31 is mounted to reciprocate through it. These various parts define a water-tight chamber. The lower end of the stuffing box is threaded into the upper end of the tubular supporting member 25 so that the chamber is rigidly supported in vertical alinement with the center of the terminals.

The plunger 31 is in the form of a rather long, slender rod of uniform diameter throughout its length. It is adapted to be reciprocated by hydrostatic pressure in response to changes in temperature of the water in the tank as will be fully explained later in the specification. In its reciprocation the plunger carries with it a current interrupter which is adapted to be interposed between the terminals 20 and 21 and withdrawn therefrom to vary the current. This current interrupter is in the form of a cylindrical tubular shield 32 of insulating material. It is connected to the plunger by means of a spider 33 formed with a central portion, encircling the lower end of the plunger, and four arms 25 which extend radially outward from the plunger and then upwardly within the inner terminal 21, and outwardly and downwardly at their upper ends. The shield is secured to the downturned portions of said ends by 30 clips 34 held in clamping engagement with the shield by screws 35. The spider 33 is loosely supported at its center by a nut 36 threaded upon the lower end of the plunger. The tubular member 25 is formed with vertical slots 37 to provide clearance for the arms of the spider, and a nut 38 is threaded upon the upper end of said member to rigidly hold it around the stuffing box. The shield is adapted to be received in the annular space 40 between the terminals 20 and 21 and in its lowermost position its lower edge rests upon the insulation 22. Its length is such that in this position it still extends a material distance above the terminals. In its uppermost 45 position it is not entirely withdrawn, its lower end remaining between the terminals.

In the use of the apparatus the closure cap 28 of the chamber 26 is removed, the plunger 31 is raised to its uppermost position so that 50 a material portion of its length projects into the chamber, and the chamber is completely filled with water at normal temperature. The cap 28 is then replaced and water is admitted to the tank through the inlet 4. Preferably the inlet remains constantly connected to the water main so that the tank will be 55 always full of water at full main pressure. The terminals and the chamber 26 are then entirely submerged, and the plunger is exposed at its outer end to the water in the tank and at its inner end to the water in the chamber. The walls of the chamber are formed of a material possessing good heat conductivity in order that a change in the 60 temperature of the water in the tank will be

accompanied by a substantially corresponding change in the water confined in the chamber.

In the initial adjustment of the apparatus, with the plunger and the insulating shield or interrupter 32 fully elevated the plunger is positively held up by the hydrostatic pressure exerted upon its lower end by the unheated water in the tank, as a descent of the plunger would cause a vacuum in the closed chamber 70 26. In this position of the plunger the spider 33 and the shield are held elevated by the nut 36 upon the plunger. The current is then free to flow across the space between the terminals, with the result that the water 75 at the lower end of the tank will be heated and will flow upwardly past the terminals and past the shield to the upper portion of the tank. Near their lower ends the terminals are formed with transverse openings 39 80 to freely admit the water to the heating space between the terminals. When the flow of heating current has continued long enough to heat the volume of water surrounding the chamber 26, heat will be conducted through the walls of the chamber to the small confined volume of water therein. The heating of the latter tends to expand it so that a hydrostatic pressure is exerted upon the upper end of the plunger. When the temperature increases to a predetermined degree 85 this pressure will overcome the opposing hydrostatic pressure upon the lower end of the plunger and move the plunger downward. The descent of the plunger permits the spider 90 33 and the shield 32 to gravitate and interpose the shield between the terminals to interrupt the flow of current. If the high temperature continues and increases sufficiently 95 the plunger will be forced down far enough 100 to permit the shield to gravitate until it abuts the insulation 22 at the bottom of the tank and entirely separates the terminals. If, however, some of the heated water is withdrawn, colder water will flow around the 105 chamber 36 arresting the expansion of the water therein and the descent of the plunger 110 and the shield.

If the temperature of the water in the tank should fall to a predetermined degree, due 115 to the interruption of the current or a withdrawal of hot water, with a consequent inflow of cold water through the inlet 4, heat will be conducted from the confined volume 120 of water out through the conducting walls of the chamber to the water in the chamber. The confined water then contracts thereby reducing the pressure upon the upper end of the plunger so that the opposed hydrostatic main pressure upon the lower end of the plunger forces it upward to prevent a vacuum 125 in the chamber. The ascent of the plunger raises the shield 32, by means of the nut 36 and the spider, from between the terminals to permit a resumption of the heating 130

current therebetween. The upward movement of the plunger is limited by contact of the central portion of the spider with the gland 40 of the stuffing box.

5 Thus the current is automatically controlled in accordance with the heating requirements of the water in the tank. The current interrupter is moved to operative or inoperative position by changing hydro-
10 static pressure due to exchanges of heat between the water in the tank and the confined water in the chamber as the temperature of the former varies. The various parts are proportioned and formed to render the
15 current-controlling means properly sensitive to the temperature changes.

What I claim is:

What I claim is:

1. In a water heater, the combination of a tank; a pair of electrodes spaced apart in said tank in position to be submerged in the water; electrical conductors connected to said electrodes; an insulating shield adapted to reciprocate and to be interposed between said electrodes and to be withdrawn therefrom; normally stationary means to positively support said shield withdrawn from said electrodes independently of the water in said tank; and means actuated by changes in temperature of water in the tank to operate said supporting means to interpose said shield between said electrodes when the temperature of the water in the tank rises, and to positively withdraw said shield when the temperature of the water is reduced.
2. In a water heater, the combination of a tank; a pair of electrodes spaced apart in said tank in position to be submerged in the water; electrical conductors connected to said electrodes; an insulating shield adapted to reciprocate and to be interposed between said electrodes and to be withdrawn therefrom; normally stationary means to positively support said shield withdrawn from said electrodes independently of the water in said tank; and means actuated by water pressure due to changes in temperature of water in the tank to operate said supporting means to interpose said shield between said electrodes when the temperature of the water in the tank rises, and to positively withdraw said shield when the temperature of the water is reduced.

55 3. In a water heater, the combination of a tank; a pair of electrodes spaced apart in said tank in position to be submerged in the water; electrical conductors connected to said electrodes; an insulating shield adapted to reciprocate and to be interposed between said electrodes and to be withdrawn therefrom; normally stationary means to 60 positively support said shield withdrawn from said electrodes independently of the water in said tank; and means actuated by fluid pressure due to changes in temperature 65 of water in the tank to operate said support-

ing means, to interpose said shield between said electrodes when the temperature of the water in the tank rises, and to positively withdraw said shield when the temperature of the water is reduced. 70

4. In a water heater, the combination of a tank; a pair of annular electrodes arranged one within the other and spaced apart in the tank in position to be submerged in the water in said tank; electrical conductors connected to said electrodes; an annular insulating shield adapted to reciprocate and to be interposed between said electrodes and to be withdrawn therefrom; normally stationary means to positively support said shield withdrawn from said electrodes independently of the water in said tank; and means actuated by changes in temperature of water in the tank to operate said supporting means to interpose said shield between said electrodes when the temperature of the water in the tank rises, and to positively withdraw said shield when the temperature of the water is reduced.

5. In a water heater, the combination of a tank; a pair of annular electrodes arranged one within the other and spaced apart in the tank in position to be submerged in the water in said tank; electrical conductors connected to said electrodes; an annular insulating shield adapted to reciprocate and to be interposed between said electrodes and to be withdrawn therefrom; normally stationary means to positively support said shield withdrawn from said electrodes independently of the water in said tank; and means actuated by water pressure due to changes in temperature of water in the tank to operate said supporting means to interpose said shield between said electrodes when the temperature of the water in the tank rises, and to positively withdraw said shield when the temperature of the water is reduced.

6. In a water heater, the combination of a tank; a pair of annular electrodes arranged one within the other and spaced apart in the tank in position to be submerged in the water in said tank; electrical conductors connected to said electrodes; an annular insulating shield adapted to reciprocate and to be interposed between said electrodes and to be withdrawn therefrom; normally stationary means to positively support said shield withdrawn from said electrodes independently of the water in said tank; and means actuated by fluid pressure due to changes in temperature of water in the tank to operate said supporting means to interpose said shield between said electrodes when the temperature of the water in the tank rises, and to positively withdraw said shield when the temperature of the water is reduced. 110 115 120 125

7. In a water heater, the combination of a tank; a pair of electrodes spaced apart in said tank in position to be submerged in the water; 130

- from; normally stationary means to positively support said shield withdrawn from said electrodes independently of the water in said tank; and means actuated by water pressure due to changes in temperature of water in the tank to operate said supporting means to interpose said shield between said electrodes when the temperature of the water in the tank rises, and to positively withdraw said shield when the temperature of the water is reduced.
15. In a water heater, the combination of a tank; a pair of annular carbon electrodes arranged one within the other and spaced apart in the tank in position to be submerged in the water in said tank; electrical conductors connected to said electrodes; an annular insulating shield adapted to reciprocate and to be interposed between said electrodes and to be withdrawn therefrom; normally stationary means to positively support said shield withdrawn from said electrodes independently of the water in said tank; and means actuated by changes in temperature of water in the tank to operate said supporting means to interpose said shield between said electrodes when the temperature of the water in the tank rises, and to positively withdraw said shield when the temperature of the water is reduced.
25. 16. In a water heater, the combination of a tank; a pair of annular carbon electrodes arranged one within the other and spaced apart in the tank in position to be submerged in the water in said tank; electrical conductors connected to said electrodes; an annular insulating shield adapted to reciprocate and to be interposed between said electrodes and to be withdrawn therefrom; normally stationary means to positively support said shield withdrawn from said electrodes independently of the water in said tank; and means actuated by water pressure due to changes in temperature of water in the tank to operate said supporting means to interpose said shield between said electrodes when the temperature of the water in the tank rises, and to positively withdraw said shield when the temperature of the water is reduced.
35. 17. In a water heater, the combination of a tank; a closed water chamber in said tank in position to be submerged in the water therein; a pair of terminals spaced apart in the tank in position to be submerged in the water in said tank; an insulating shield adapted to reciprocate and to be interposed in between said terminals and to be withdrawn therefrom; means extending into the closed chamber and adapted to be reciprocated therein and to be actuated by pressure due to changes in temperature of the water in said closed chamber; and means connecting said reciprocable means to the said insulating shield whereby said shield will be interposed between the electrodes when the
- water in the closed chamber is raised in temperature, and will be withdrawn from between said electrodes when the said temperature is lowered.
18. In a water heater, the combination of a tank; a closed water chamber in said tank in position to be submerged in the water therein; a pair of terminals spaced apart in the tank in position to be submerged in the water in said tank; an insulating shield adapted to reciprocate and to be interposed in between said terminals and to be withdrawn therefrom; a plunger extending into the closed chamber and adapted to be reciprocated therein and to be actuated by pressure due to changes in temperature of the water in said closed chamber; and means connecting said reciprocable plunger to the said insulating shield whereby said shield will be interposed between the electrodes when the water in the closed chamber is raised in temperature, and will be withdrawn from between said electrodes when the said temperature is lowered.
20. 19. A liquid-heating device comprising means forming a liquid-tight chamber, with a heat-conducting wall; means to support said chamber within a liquid tank with its heat-conducting wall exposed to liquid in the tank at its outer face and to liquid in said chamber at its inner face; a plunger mounted to reciprocate through one wall of said chamber and having its inner end exposed to the liquid in the chamber and its outer end exposed to the liquid in the tank; electrical means to heat the water in the tank; and means operated by the reciprocation of said plunger to vary the heating effect of said electrical means.
25. 20. A liquid-heating device comprising means forming a liquid-tight chamber, with a heat-conducting wall; means to support said chamber within a liquid tank with its heat-conducting wall exposed at its outer face to liquid in the tank and at its inner face to liquid in the chamber; a shiftable member to vary the size of said chamber, subject at opposite faces to opposing pressures of the liquid in the tank and the liquid in the chamber; electrical means to heat the liquid in the tank; and means operated by the movements of said shiftable member to vary the heating effect of said electrical means.
30. 21. A liquid-heating apparatus comprising a tank; a pair of tubular, concentric, spaced electric terminals mounted in said tank in upstanding positions; means forming a liquid-tight chamber, with heat-conducting walls; means supporting said chamber within the tank in a position over the center of the terminals; a plunger mounted to reciprocate vertically through the lower wall of the chamber and have its inner end exposed to liquid in the chamber and its outer end exposed to liquid in the tank; an annular insulating bar-

rier carried by said plunger to reciprocate with it and adapted to be interposed between the terminals and interrupt the current when the plunger is moved down.

22. A liquid-heating apparatus comprising a tank; a pair of tubular, concentric, spaced electric terminals mounted in said tank at the lower end thereof in upstanding positions; means forming a liquid-tight chamber with 10 heat-conducting walls; means supporting said chamber in the tank; a plunger mounted to reciprocate vertically through one wall of said chamber and have its inner end exposed to liquid in the chamber and its outer end 15 exposed to liquid in the tank; an insulating barrier carried by said plunger to reciprocate with it and adapted to be interposed between the terminals and interrupt the current when the plunger is moved down; a liquid 20 inlet at the lower end of the tank, opening into the space defined by the inner terminal; and a liquid outlet at the upper end of the tank.

23. In a water heater, the combination of 25 a tank; a pair of electrodes spaced apart in said tank in position to be submerged in the water; electrical conductors connected to said electrodes; an insulating shield adapted to reciprocate and to be interposed between said 30 electrodes and to be withdrawn therefrom; normally stationary means to positively support said shield withdrawn from said electrodes; and means actuated by water pressure due to changes in temperature of water 35 in the tank to operate said supporting means to gradually and progressively interpose said shield between the said electrodes as the temperature of the water in the tank rises, and to positively, gradually and progressively 40 withdraw said shield as the temperature of the water is reduced.

24. In a water heater, the combination of 45 a tank; a pair of annular electrodes arranged one within the other and spaced apart in the tank in position to be submerged in the water in said tank; electrical conductors connected to said electrodes; an annular insulating shield adapted to reciprocate and to be interposed between said electrodes and to be withdrawn 50 therefrom; means to positively support said shield withdrawn from said electrodes; and means actuated by fluid pressure due to changes in temperature of water in the tank to gradually and progressively interpose said shield between said electrodes when the temperature of the water in the tank rises, and to positively, gradually and 55 progressively withdraw said shield when the temperature of the water is reduced.

60 In testimony whereof I hereunto affix my signature.

MANSFIELD C. CRAWLEY.
